[57] ABSTRACT

A diaphragm assembly for use in providing inertial dampening and valve action in an internal combustion engine muffler includes a flexible diaphragm element which is mounted over a centrally located post in concentric relationship therewith. The central post is supported on an outer ringshaped member by means of a spider structure. The edges of the diaphragm element abut against the ring member in response to back pressure from the ambient atmosphere to effectively provide a closing action. These edges are forced away from ring member by exhaust gas pressure, thus providing opening action to permit release of the exhaust gases.

DIAPHRAGM SILENCER ASSEMBLY FOR ENGINE MUFFLER

This application is a Continuation in Part of our application Ser. No. 296,072, filed Oct. 10, 1972, now U.S. Patent No. 3,779,340.

This invention relates to internal combustion engine mufflers, and more particularly to a diaphragm assembly for use in such a muffler.

In our application Ser. No. 296,072 filed Oct. 10, 1972, a muffler is described which utilizes a diaphragm assembly having one or more diaphragm elements for providing inertial dampening and affording valve action which greatly improves the performance of the muffler. The present invention involves a diaphragm assembly which operates in the same general manner as those described in our aforementioned prior application but which utilizes only a single diaphragm element with a heat shield and a somewhat different structural implementation. The device of the present invention, while less effective in its silencing action than diaphragm assemblies having a plurality of diaphragm elements, nevertheless affords the advantage of greater simplicity and economy of construction.

It is therefore the principle object of this invention to provide a diaphragm assembly for use in an internal combustion engine muffler of simpler and more economical construction.

Other objects of my invention will become apparent as the description proceeds in connection with the accompanying drawings, of which:

FIG. 1 is an elevational, cross-sectional view of a preferred embodiment of the invention as incorporated into a muffler assembly;

FIG. 2 is a view taken along the plane indicated by 2-2 in FIG. 1; and

FIG. 3 is a plan view of the preferred embodiment of the diaphragm assembly of the invention showing the side thereof opposite to that shown in FIG. 2.

Referring now to the figures, frame 11 includes a ring portion 12. Extending from ring portion 12, in a direction substantially normal to the surface of the ring, is an annular lip 14. Lip 14 has a pair of indentations 14a formed therein which are used to retain the ring against rotation in muffler assembly 20. Extending inwardly from ring 12 are arms 17 which form a spider assembly which supports a centrally located ring 18. Central post 22 is supported in ring 18 by means of flanged end portion 25 of the post assembly which is flared and pressed against the face of ring 18 to effectively form a retaining rivet.

Central post 22 has, integrally formed therewith, an end disc 28. Fitted over central post 22 is a flexible diaphragm element 30 which may be made of a suitable high temperature silicone rubber. A heat shield 31 for the diaphragm which may be of stainless steel is mounted in front of the diaphragm. This shield serves not only to protect the diaphragm from the heat of the exhaust gasses but also operates as a sound reflector which it has been found reduces the noise level. The central portion 30a of the diaphragm element is widened so that it fits snugly between disc 28 and ring 18 in resilient retention therebetween. The outer portions 30b of the diaphragm element are free to move axially in response to gas pressure. In the absence of any pressure differential, between the opposite faces thereof, the diaphragm element is resiliently retained in the position shown in FIG. 1, with the edges thereof abutting

against ring 12. Diaphragm 30 has an annular lip 30c running around the periphery thereof which seals against ring 12 in response to pressure on the outer surface of the diaphragm.

5 Diaphragm 30, further, has a plurality of apertures 30d formed therethrough which are utilized to provide pressure relief in handling high back pressures. Surrounding each of apertures 30d is a hexagonal indentation 30e formed in the surface of the diaphragm. These indentations serve to break up and diffuse sound waves, thus aiding in the silencing action.

The diaphragm assembly is retained at the exhaust end of muffler 20 means of an annular snap ring 40 which is retained in annular indentation 41 formed along the edge portion of the main body 20 of the muffler.

Exhaust gas is fed from central muffler chamber 45 through flared outlet 46 to the diaphragm assembly. The exhaust pressure forces the outer portions of diaphragm element 30 outwardly with lip portion 30c moving away from its engagement with ring 12. The outward movement of diaphragm element 30 is limited by disc 28 as indicated by the dotted lines. Where there is a back pressure, i.e. a positive pressure differential between the ambient atmosphere and muffler chamber 45, the outer portions of the diaphragm element are forced inwardly with lip 30c sealing against ring 12, thus alleviating noise effects incidental to such back pressure effects. Apertures 30d provide pressure relief in the case of high back pressures, thus preventing distortion of the diaphragm which might result in damage thereto. Ribs 30f may be provided on the diaphragm to stiffen its structure.

35 The device of the invention thus provides a simple and economical diaphragm assembly for providing inertial dampening and valving in response to gas pressure to improve the silencing action of an internal combustion engine muffler.

40 While the invention has been described and illustrated in detail, it is to be clearly understood that this is intended by way of illustration and example only, and is not to be taken by way of limitation, the spirit and scope of this invention being limited only by the terms 45 of the following claims.

We claim:

1. A diaphragm assembly for use in an engine muffler to provide inertial dampening and to afford valve action comprising:

a flexible circular diaphragm element having a plurality of apertures formed therethrough to provide pressure relief for high back pressure, a ring member having a flat faced portion and an inside diameter slightly less than the diameter of said diaphragm element, a central post,

a spider structure for supporting said central post from said ring member, said diaphragm element being mounted over said central post in concentric relationship therewith, with the peripheral edges of said diaphragm element abutting against the flat faced portion of said ring member,

60 a member attached to one end of said central post for limiting the movement of said diaphragm element in response to the exhaust gas pressure, and means for feeding the exhaust gas received by the muffler from the engine to said diaphragm element,

the outer portions of said diaphragm element being free to move away from said ring member in response to exhaust gas pressure, and with the edges thereof in sealing engagement against said ring in response to back pressure from the ambient atmosphere.

2. The device of claim 1 wherein said diaphragm elements have a plurality of indentations formed on the

surface thereof facing towards the exhaust gas for breaking up sound waves.

3. The device of claim 2 and further including a heat shield member mounted between said diaphragm element and the means for feeding the exhaust gas thereto, said heat shield member shielding said diaphragm element from the heat of the exhaust gasses.
